RECOVERY OF HIGHER FATTY ALCOHOLS

Benjamin H. Thurman, Charlotte, N. C., assignor
to Refining, Inc., Reno, Nev., a corporation of
Nevada

Application April 1, 1941, Serial No. 386,388

13 Claims. (Cl. 260—418)

This invention relates to the recovery of higher fatty alcohols, and more particularly to a process by which oils or fats containing fatty acid radicals in combination with higher fatty alcohols are treated to form soap from the fatty acids and to recover the higher fatty alcohols substantially free from impurities.

Certain oils or fats, particularly oils known as sperm oils from certain whales, for example, whales of the genera Physeter and Hyperoodon, contain esters of certain saturated and unsaturated fatty alcohols with fatty acids, in addition to or in complete substitution of glycerol esters of fatty acids. These higher fatty alcohols, which contain from 16 to 20 carbon atoms per molecule, are insoluble in water and soluble in alcohol and ether, whereas glycerine is soluble in water. They occur as esters of saturated and unsaturated fatty acids containing from 10 to 20 carbon atoms per molecule. They have heretofore been recovered from sperm oils by saponifying the same with caustic alkali at 110 to 120° C., the sodium salts thus formed being dissolved in boiling water and thereafter decomposed with hot concentrated solutions of calcium chloride in excess, whereby the alcohols and insoluble calcium soaps of the fatty acids precipitate out together. The precipitate is filtered, dried and extracted with benzene or alcohol, the solvent is then driven off by heating, leaving the crude alcohol, which is then purified by crystallization from dilute alcohol. Such a process is time consuming and expensive. The sperm oil is extremely difficult to saponify in ordinary soap kettle operations and the process requires the employment of expensive solvents, produces less valuable calcium soaps and any glycerine present is dissolved in dilute and impure solutions containing large amounts of salts, such that it is expensive and difficult to recover the glycerine.

The present process directly produces relatively pure higher fatty alcohols, a high quality sodium soap having good detergent properties, also relatively pure glycerine waters from which glycerine may be easily recovered, and does not require the use of solvents. The process is preferably carried out as a continuous operation in which the higher fatty alcohols, as well as glycerine, are vaporized from the soap and condensed in relatively pure form, and high quality soap in substantially anhydrous form produced.

It is, therefore, an object of the invention to provide a process in which fats or oils containing higher fatty alcohol esters of fatty acids are treated to saponify the fatty acids and the higher fatty alcohols recovered without the employment of solvents or the formation of insoluble soaps.

Another object of the invention is to provide a process in which higher fatty alcohols are continuously vaporized from admixture with soap

so as to recover both the soap and the alcohols in substantially pure form.

Another object of the invention is to provide a process of continuously saponifying oils and fats containing higher fatty alcohol esters of fatty acids in which the alcohols are recovered directly from soluble soap and the soap produced in substantially anhydrous form.

There are two types of sperm oils, one coming from the head and the other from the blubber of whales. The head oil is more saturated in both its alcoholic and acidic components and contains the following alcohols in the form of esters with fatty acids: about 50% of cetyl alcohol $C_{16}H_{33}OH$, about 10 to 12% of hexadecenyl alcohol $C_{16}H_{31}OH$, about 10 to 12% of octadecyl alcohol $C_{18}H_{37}OH$, about 25% of octadecenyl alcohol $C_{18}H_{35}OH$, about 2 to 3% of glycerine and the remainder as eicosenyl alcohol $C_{20}H_{39}OH$. The fatty acids combined with the alcohols include about 4% of capric acid $C_{10}H_{20}O_2$, about 18% of lauric acid $C_{12}H_{24}O_2$, about 6% of the corresponding unsaturated acid $C_{12}H_{22}O_2$, about 12% of myristic acid $C_{14}H_{28}O_2$, about 16% of the corresponding unsaturated acid $C_{14}H_{26}O_2$, about 8% of palmitic acid $C_{16}H_{30}O_2$, about 17% of palmitoleic acid $C_{16}H_{28}O_2$, a small amount of stearic acid C_{18} , and about 10% of oleic acid $C_{18}H_{34}O_2$, and a small amount of unsaturated acid $C_{20}H_{38}O_2$.

The blubber oil, as stated above, is less saturated, and the alcoholic constituents include about 20% of cetyl alcohol, about 20% of hexadecenyl alcohol, a small amount of octadecyl alcohol, about 65% of octadecenyl alcohol and about 10% of unsaturated alcohols containing 20 carbon atoms as well as 3 to 4% glycerine. The fatty acids resemble those of ordinary whale oil more closely than those of sperm head oil but are not so highly unsaturated as the former. They contain about 1% of lauric acid, about 3% of myristic acid, about 3% of the corresponding unsaturated acid $C_{14}H_{26}O_2$, about 8% palmitic acid, about 24% of palmitoleic acid, about 35% of oleic acid and about 10 to 12% each of arachidic (C_{20}) and behenic (C_{22}) acid series.

Thus, the head oil contains about 26% of glycerides and 74% of higher fatty esters and the blubber oil contains about 34% of glycerides and 66% of higher fatty acid esters. It will be noted that the alcohols of the head oil are predominantly saturated alcohols, mostly cetyl alcohol, whereas the alcohols of the blubber oil are predominantly an unsaturated alcohol, namely octadecenyl, and that the acids of the blubber oil are much less saturated than those of the head oil. Either of these oils may be hydrogenated to saturate both the alcoholic and acidic components to any desired degree before treating the same by the present process so that more highly saturated alcohols are produced, as well as soap containing more highly saturated acids,

or the alcoholic component can be hydrogenated after separation from the soap.

The present invention will be described in conjunction with a suitable apparatus diagrammatically shown in the accompanying drawing. Referring to the drawing, a source of supply of oils containing esters of higher fatty alcohols and fatty acids is shown as a tank 10 provided with a heating coil 11 so that the oils may be maintained in flowable condition. A source of supply for alkalies, such as caustic soda solution, is shown as a tank 12 provided with a heating coil 13 so that the alkali solution will be brought to the desired temperature. In an operation including continuous saponification, proportioned streams of oil and alkali may be withdrawn from the tanks 10 and 12 through pipes 14 and 15, respectively, by proportion pumps 16 and 17, respectively, and forced under pressure through preheating coils 18 and 19, respectively. The pumps 16 and 17 are shown, by way of example, as being driven by a variable speed electric motor 20 with a variable speed device 21 positioned between the pumps so that any desired amounts and proportions of oil and alkali can be introduced into the process. Any other type of known or suitable proportioning mechanism can be substituted for that shown.

The heating coils 18 and 19 may be heated by any suitable means, for example, burners 22 for gaseous or liquid fuel. The oil is preferably heated in the coil 18 under flow conditions to avoid local overheating to temperatures ranging from 250 to 300° F. so as to provide for rapid saponification when the oil is contacted with alcohol and to also prevent the formation of viscous soap masses, which tend to form at lower temperatures. The alkali solution is also preferably preheated in coil 19 so as not to chill the oil when brought in contact therewith. Since the alkali solution is extremely corrosive at high temperatures it is preferred to preheat the oil to a somewhat higher temperature than that necessary to produce a flowable soap mixture to enable the alkali solution to be preheated to a somewhat less temperature, for example, temperatures not in excess of 200° F., and still form a flowable soap mixture. The preheated oil and alkali are preferably mixed in a closed flow mixer 23 by jetting a stream of one material into a stream of the other although any type of flow mixer, for example, a closed mechanical mixer provided with agitators, can be employed so long as air is prevented from contacting the materials at the high temperatures employed. Saponification of the oil is rapid and substantially complete in the mixer 23 and a flowable mixture containing soap, higher fatty alcohols and small amounts of glycerine is produced which may also contain portions of unsaponified oil. A pump 24 is preferably employed for forcing the resulting mixture through another heating device such as a coil 25 heated in a desired manner, for example, by burner 22. The temperature of the mixture is increased in the coil 25 and saponification of any unsaponified materials completed. It is preferred not to raise the temperature in the coil above that at which decomposition of esters or fatty acids will take place. Thus, temperatures between 350 to 420° F. can be employed. It is preferred to maintain a relatively high pressure in this coil to prevent the formation of substantial amounts of vapors therein; thus pressures ranging between 125 to 350 pounds per square inch can be satisfactorily

employed. The pump 24 produces a further mixing action, and any further mixing which takes place during stream flow in the coil 25, in conjunction with the high temperatures employed, results in a substantially complete saponified mixture leaving the coil 25. The substantially completely saponified mixture may then be pumped by means of a pump 26 through another heating device shown as a heating coil 27 in which the temperature of the mixture is further increased. The temperature employed in coil 27 will ordinarily range between 500 and 650° F. although in certain cases temperatures as high as 700° F. may be necessary. Since the mixture has previously been substantially completely saponified, decomposition of esters or fatty acids is avoided. Heat may be applied to the heating coil 27 by a burner 22.

Substantially all of the higher fatty alcohols, glycerine and water, as well as any other vaporizable materials contained in the mixture, are evaporated when the heated mixture is discharged into an evaporating chamber 28. The pressure in coil 27 may be as low as or somewhat lower than that in the coil 25 so that a portion of the vaporizable materials are vaporized in the coil 27, thus enabling more heat to be supplied to the mixture at the temperature employed and reducing the amount of heat necessary to be supplied in the evaporating chamber 28 in order to vaporize substantially all of the vaporizable materials. Pressures ranging from 250 pounds down to almost atmospheric pressure at the outlet of the coil can be employed, although due to the frictional head in the coil, the pressures at the inlet thereof will be somewhat higher.

A vacuum is preferably maintained within the evaporating chamber 28 by removing vapors through the pipe 29 and condensing the same in one or more condensers 30 supplied with receivers 31 connected to a vacuum pump 32. The evaporating chamber is also preferably supplied with a heating jacket 32 through which any desired heating medium, such as superheated steam or heated mineral oil, may be circulated by pipes 34 and 35. The heated mixture coming from the coil 27 is preferably directed against the heated walls of the evaporating chamber by nozzles 36 positioned adjacent said walls. In order to completely remove the alcohols, glycerine, etc., it is usually necessary to maintain the temperature of the separated soap in the vacuum chamber sufficiently high to cause the same to be in liquid form after the vaporizable materials have been removed. Thus, temperatures between 420° and 600° F. must ordinarily be employed in the evaporating chamber. It will be noted that the liquid soap flows down the heated walls of the evaporating chamber as a film such that vapors are readily released therefrom and that the vapors can pass inwardly and upwardly to the pipe 29 through a substantially unimpeded path in the evaporating chamber.

The soap is thus deposited in the evaporating chamber in liquid anhydrous form and will continuously flow into the casing 37 of a screw conveyor 38. The casing 37 is connected to the evaporating chamber in fluid-tight relationship such that the casing 37, for example, forms a part of the evaporating chamber. A cooling jacket 39 through which any desired cooling medium, such as water, can be circulated is preferably positioned around the discharge end of the conveyor housing 37 to cool the soap being discharged therefrom, and the portion 40 of the conveyor

shaft adjacent the discharge end of the conveyor is preferably enlarged to provide a restricted passageway 41 for the cooled soap. By forcing the cooled soap through such a restricted passageway an effective vacuum seal is formed so that the soap can be continuously removed from the evaporating chamber during operations without breaking the vacuum. A manually operated valve 42 in the discharge end of the conveyor housing 37 is preferably provided so that it may be closed during starting and stopping of the process to maintain a vacuum in the evaporating chamber when insufficient soap is present in the restricted passageway 41. The valve 42 is normally open during operation of the process. The soap discharged from the conveyor housing 41 should be sufficiently cooled so that it is not damaged by contact with the atmosphere and in general its temperature must be as low as 120° F. The soap produced is readily soluble in water and can be hydrated if desired to form bar, powdered or granular soap. It is light colored and of an agreeable odor and has excellent detergent properties.

The vaporizable materials are condensed in the condenser 30 and cooled in the receiver 31. The condensate will settle cleanly into an upper layer of pale yellow fatty alcohol and a lower layer of water containing a small amount of glycerine and soap. It may be withdrawn from the receiver 31 through a pipe 43 by any desired means, such as a pump 44. For example, the condensate can be continuously withdrawn and subjected to continuous centrifugal separation in a centrifugal separator 45. The higher fatty alcohols are continuously discharged as the lighter affluent through a spout 46 into a receptacle 47 and the water, soap and glycerine layer discharged as the heavier affluent through a spout 48 into a receiver 49. A somewhat cleaner separation can be effected by the centrifugal separator and the entire process is continuous from the introduction of the materials therein to the production of high quality, higher fatty alcohols and high quality anhydrous soap. The water layer containing small amounts of soap and glycerine may be concentrated and glycerine separated from the soap in any desired manner. This can be simply done as the glycerine and soap are not contaminated by large amounts of other impurities.

As a specific example of a process in accordance with the present invention, sperm oil in the tank 10 was heated by the coil 11 to a temperature of 190° F. so as to render the same flowable and reduce the amount of heat which was necessary to add during the rest of the process. A solution of 31.76% sodium hydroxide was supplied from the tank 12 at approximately room temperature. Approximately 8 pounds of sperm oil per minute was pumped through the coil 18 wherein it was preheated to 280° F. The speed of the proportioning pump 17 was adjusted until the proper proportion of lye solution to produce a substantially neutral soap was pumped through the coil 19 in which it was preheated to 175° F. These materials were mixed in a flow mixer 23 and heated in the coil 25 so that the discharge temperature therefrom was 450° F. It was then pumped through the coil 27 wherein additional heat was supplied and the mixture was discharged from the coil at 585° F. Mineral oil was used in the heating jacket 33 around the evaporating chamber 28 and was maintained at a temperature of 475° F. The vapors from the

evaporating chamber had a temperature of 450° F. During this run the pressure at the entrance of the coils 18 and 19 was 200 pounds per square inch, the pressure at the outlet of coil 25 was 250 pounds per square inch and the pressure on the mixture just before it entered the evaporating chamber 28 was 40 pounds per square inch. The vacuum in the evaporating chamber was maintained at 28½ inches mercury.

The soap produced was light in color, readily soluble in water and has good detergent properties. The condensate was milky when withdrawn from the receiver 31 but settled cleanly into an upper layer of pale yellow fatty alcohols and a lower one of water containing a small amount of soap and glycerine. Such a condensate is readily susceptible to centrifugal separation.

The fatty alcohols resulting from the settling or centrifugal separating operation are mixtures of the higher fatty alcohols in substantially the same proportions that occur in the original oil, and this mixture will depend upon the type of sperm oil employed. If substantially pure cetyl alcohol, for example, is desired, the head oil would be employed which contains nearly 50% of cetyl alcohol, and the various other alcohols can be separated therefrom by fractional distillation under vacuum conditions. Another way to produce substantially pure cetyl alcohol is to first produce spermaceti from the head oil by chilling the sperm oil for several weeks and then pressing it cold (about 0° C.), then repressing the residual cakes at approximately 15° C. to remove more oil. The residue is largely spermaceti which may be purified by a third pressing at a somewhat higher temperature. The yield of spermaceti is generally only 10 to 15% of the original oil and consists substantially all of cetyl palmitate. By using this material as the starting material, substantially pure cetyl alcohol can be obtained, but in practice it is preferred to treat the oil containing the various fatty alcohols so as to first produce a mixture of said alcohols, which may be later separated if desired. This mixture can be hydrogenated if it is desired to produce a mixture of wholly or partially saturated alcohols having properties very similar to pure cetyl alcohol.

Several modifications of the above described process are possible. For example, the sperm oil and saponification reagent may be mixed in proper proportions in a batch mixing device, such as a soap kettle, wherein they are heated or maintained at a temperature sufficiently high, or in the presence of sufficient water, or both, to form a flowable mixture. That is, temperatures approaching the boiling point of water may be employed. Some saponification may take place in such kettle but complete saponification is unnecessary. By maintaining sufficient agitation, a substantially uniform mixture may be continuously pumped from the kettle through the coils 25 and 27 wherein substantially complete saponification is effected and the temperature raised sufficient to cause separation of the alcohols as vapors in the evaporating chamber 28, as above described. Also, the coils 25 or 27 may be employed to completely saponify a mixture from either a continuous or batch mixer and the resulting soap mixture cooled, for example, in a cooling coil, before contacting the same with the atmosphere, and then treated to separate alcohols and form insoluble soap in accordance with prior practices above described. This procedure enables a substantially completely saponified mix-

ture to be quickly produced but does not avoid the employment of solvents or the production of less valuable insoluble soap. The combination of rapid and substantially complete saponification with vaporization of the alcohols from soluble soap does, however, rapidly produce high quality soluble soap and substantially pure alcohols.

While in the preferred operation the oil is pre-heated in the heating device 18 and the mixture subsequently heated in the heating device 25 to a temperature which insures substantially complete saponification therein, it is apparent that all of the heat necessary for such reaction can be supplied in the preheating coil 18 since the reaction temperatures are below those which cause substantial decomposition of fatty materials under the conditions in the present process. Thus the temperature of the saponifiable material can be raised in the preheating coil to a temperature which, when the heated material is mixed with the saponifying material, will produce the desired reaction temperature in the coil 25, for example, 350 to 420° F., so that no further heat need be applied in the coil 25 which can function merely as a reaction zone. The reacted mass can then either be further heated in the heating device 27 in order to separate vapors in the vapor separating zone 28, it can be introduced directly into the vapor separating zone to at least partially separate vapors, or can be cooled and discharged from the system.

This application is a continuation-in-part of my copending application Serial No. 180,231.

While I have disclosed the preferred embodiments of my invention, it is understood that the details thereof may be varied within the scope of the following claims:

I claim:

1. The process of producing substantially pure higher fatty alcohols and high quality soap, which comprises, forming a mixture of an oil containing higher fatty alcohol esters of fatty acids and sufficient alkali to substantially completely saponify said esters, saponifying said esters by pumping a stream of said mixture through a heating zone under pressure, supplying sufficient heat to said heating zone to substantially completely saponify said mixture and raise the temperature thereof sufficient to cause said alcohols to separate in vapor form as soon as said pressure is reduced, any heating of oil or fatty material substantially above the boiling point of water being effected during stream flow thereof, discharging said heated mixture into an evaporating zone at a lower pressure wherein said alcohols are substantially immediately separated in vapor form from the resultant soap, and continuously withdrawing and condensing said vapors.

2. The process of producing substantially pure mixtures of higher fatty alcohols, which comprises, forming a mixture of an oil containing higher fatty alcohol esters of fatty acids and a saponifying reagent, saponifying said esters by continuously pumping a stream of said mixture under pressure through a heating zone, supplying sufficient heat to said zone and maintaining said mixture under sufficient conditions of movement to rapidly and substantially completely saponify said mixture, thereafter pumping the resulting mixture through a second heating zone and increasing the temperature of said mixture sufficient to cause said fatty alcohols to be separated in vapor form as soon as said pressure is reduced, discharging the resulting heated mix-

ture into an evaporating zone under a reduced pressure wherein said higher fatty alcohols and water are substantially immediately separated in the form of vapors from the resulting soap, continuously removing said vapors from said evaporating zone and condensing the same to form a liquid mixture containing said higher fatty alcohols and water, and separating said higher alcohols from said water by difference in specific gravity.

3. The process of producing soap and substantially pure mixtures of higher fatty alcohols from oils containing substantial quantities of higher fatty alcohol esters of fatty acids, which comprises, forming a mixture of said oil and an aqueous saponifying reagent, saponifying said esters by pumping a stream of said mixture under pressure through a heating zone, imparting sufficient heat in said zone to substantially completely saponify said mixture and raise the temperature thereof sufficient to cause said higher fatty alcohols and water to be separated in the form of vapor from the resulting soap when the heated mixture is introduced into an evaporating chamber in which a vacuum is maintained, introducing said heated mixture into said evaporating chamber, maintaining the temperature in said evaporating chamber sufficiently high to cause said soap to be deposited in substantially anhydrous molten form after said alcohols and water have been separated therefrom, continuously withdrawing said vapors from said evaporating zone at a rate sufficient to maintain said vacuum, condensing said vapors to form a mixture of higher fatty alcohols and water, separating said alcohols from said water by difference in specific gravity, continuously removing said soap from said evaporating chamber without breaking said vacuum and cooling said soap during removal and while still anhydrous below a temperature at which it will be damaged by contact with the atmosphere.

4. The process of saponifying oils consisting predominantly of higher fatty alcohol esters of fatty acids to produce high quality soap and substantially pure mixtures of higher fatty alcohols, which comprises, heating a flowing stream of said oils out of contact with the atmosphere to a temperature between approximately 250° and 300° F. at which substantially instantaneous saponification of said oils will take place when the same are mixed with a saponifying reagent, continuously admixing a stream of saponifying reagent with a stream of the heated oils to produce said saponification, thereafter raising the temperature of the resulting mixture sufficient to cause substantially immediate separation of water and said alcohols in vapor form from said soap under vacuum conditions, introducing said heated mixture into an evaporating chamber in which a vacuum is maintained and continuously separating said vapors from said soap and withdrawing the same from said evaporating chamber at a rate sufficient to maintain said vacuum, condensing said vapors to form a mixture of water and higher fatty alcohols, and separating said higher fatty alcohols from said water by difference in specific gravity.

5. The process of saponifying oils containing substantial quantities of higher fatty alcohol esters of fatty acids, which comprises, saponifying said oil by flowing a stream of a mixture of said oil and sufficient alkali to substantially completely saponify said esters through a heating zone under pressure, maintaining sufficient

movement of the resulting mixture in said heating zone and supplying sufficient heat thereto to substantially completely saponify said mixture to form soap and liberate said alcohols, any heating of the oils or mixture containing fatty materials to a temperature substantially above the boiling point of water being effected during stream flow thereof and thereafter separating said alcohols from said soap.

6. The process of saponifying oils containing substantial quantities of higher fatty alcohol esters of fatty acids, which comprises, forming a mixture of said oils and sufficient alkali to substantially completely saponify the same, saponifying said mixture by pumping a stream of said mixture through a heating zone under pressure, supplying sufficient heat to said mixture in said heating zone to substantially completely saponify the same while maintaining sufficient movement of said mixture in said heating zone to prevent local overheating thereof, any heating of the oils or mixture containing fatty materials to a temperature substantially above the boiling point of water being effected during stream flow thereof and thereafter separating alcohols liberated during said saponification from said soap.

7. The process of saponifying oils containing substantial quantities of higher fatty alcohol esters of fatty acids to produce soap and higher fatty alcohols, which comprises, continuously mixing a stream of said oil and a stream of said alkali at an elevated temperature and out of contact with the atmosphere, passing the resulting mixture through a heating zone under pressure and with sufficient movement to maintain a substantially uniform mixture, supplying sufficient heat to said mixture in said heating zone to substantially completely saponify said oil to form soap and liberate said alcohols, any heating of the oils or mixture containing fatty materials to a temperature substantially above the boiling point of water being effected during stream flow thereof.

8. The process of saponifying oils containing substantial quantities of higher fatty alcohol esters of fatty acids to produce soap and higher alcohols, which comprises, continuously mixing a stream of said oil and a stream of said alkali at an elevated temperature and out of contact with the atmosphere, passing the resulting mixture through a heating zone under pressure and with sufficient movement to maintain a substantially uniform mixture, supplying sufficient heat to said mixture in said heating zone to substantially completely saponify said oil to form soap and liberate said alcohols, any heating of the oils or mixture containing fatty materials to a temperature substantially above the boiling point of water being effected during stream flow thereof and thereafter separating said alcohols from said soap.

9. The process of saponifying sperm oil to produce high quality soap and substantially pure higher fatty alcohols, which comprises, forming a mixture of said sperm oil and sufficient alkali to substantially completely saponify said oil, saponifying said oil by pumping a stream of said mixture through a heating zone under pressure, supplying sufficient heat to said heating zone to substantially completely saponify said oil and to raise the temperature of the resulting soap mixture sufficient to cause the alcohols liberated during saponification to be separated in vapor form from said soap as soon

5 as said pressure is reduced, any heating of the oils or mixture containing fatty materials to a temperature substantially above the boiling point of water being effected during stream flow thereof, discharging the heated soap mixture into an evaporating zone wherein a vacuum is maintained and said alcohol is separated in vapor form from said soap and continuously withdrawing and condensing said vapors to maintain said vacuum.

10. The process of saponifying sperm oil, which comprises, forming a mixture of said oil and sufficient alkali to substantially completely saponify said oil, saponifying said oil by continuously pumping said mixture through an elongated heating zone under pressure, and supplying sufficient heat to said heating zone and maintaining said mixture in said zone in sufficient state of movement to substantially completely saponify said mixture, any heating of the oils or mixture containing materials to a temperature substantially above the boiling point of water being effected during stream flow thereof.

11. The process of saponifying oils containing substantial quantities of higher fatty alcohol esters of fatty acids, which comprises, forming a mixture of said oil and sufficient alkali to substantially completely saponify said oil, saponifying said oil by continuously pumping said mixture through a reaction zone under pressure, maintaining sufficient movement of said mixture in said reaction zone and subjecting the mixture therein to a sufficiently high temperature to substantially completely saponify said mixture, any heating of the oils or mixture containing fatty material to a temperature substantially above the boiling point of water being effected during stream flow thereof.

12. The process of saponifying oils containing substantial quantities of higher fatty alcohol esters of fatty acids, which comprises, saponifying said oil by flowing a stream of a mixture of said oil and sufficient alkali to substantially completely saponify said esters through a reaction zone under pressure, maintaining sufficient movement of the resulting mixture in said heating zone and preheating at least said esters prior to mixing the same with said alkali to supply sufficient heat to said mixture in said zone to substantially completely saponify the same, any heating of the oils or mixture containing fatty materials to a temperature substantially above the boiling point of water being effected during the stream flow thereof.

13. The process of saponifying oils containing substantial quantities of higher fatty alcohol esters of fatty acids, which comprises, forming a mixture of said oil and sufficient alkali to substantially completely saponify said oil, saponifying said oil by continuously pumping said mixture through a reaction zone under pressure, maintaining sufficient movement of said mixture in said reaction zone and subjecting the mixture therein to a sufficiently high temperature to substantially completely saponify said mixture, any heating of the oils or mixture containing fatty material to a temperature substantially above the boiling point of water being effected during stream flow thereof, further heating the substantially completely saponified mixture and separating the liberated alcohols in vapor form from the resultant soap.
